UNITED STATES PATENT OFFICE.

LEONARD A. YOUNG, OF DETROIT, MICHIGAN.

UPHOLSTERY SPRING CONSTRUCTION.

1,137,106.

Specification of Letters Patent. Patented Apr. 27, 1915.

Application filed November 4, 1913. Serial No. 799,103.

To all whom it may concern:

Be it known that I, LEONARD A. YOUNG, a citizen of the United States of America, residing at Detroit, in the county of Wayne 5 and State of Michigan, have invented certain new and useful Improvements in Upholstery Spring Construction, of which the following is a specification, reference being had therein to the accompanying drawings.

10 This invention relates to an upholstery spring structure in which the disposition of the edge rolls of the upholstery filling and the support afforded the same are such that the seat retains its shape even under heavy 15 service.

A further feature of the construction is a reinforcement of the body springs by auxiliary springs so arranged as to transmit any local load excess throughout the 20 structure and at the same time reinforce the body springs in cushioning against and resisting further deflection.

The invention consists in the matters hereinafter set forth and more particularly 25 pointed out in the appended claims.

In the drawings, Figure 1 is a plan view of a spring seat structure that embodies features of the invention with the upholstery covering thereto and the supports for the latter removed to give clear view; Fig. 2 is a view in end elevation, partially broken away, of the parts shown in Fig. 1, with the addition of an edge roll and the support and securing means of the latter; Fig. 3 is a 35 fragmentary view, partially broken away and partially in plan, featuring the details of support of the edge roll; Figs. 4, 5, 6 and 7 are views in detail of various methods of securing the edge roll in place; Fig. 8 is a view in detail, enlarged and in section, showing the method of securing the roll supporting members; Fig. 9 is a view in detail of a preferred form of arch reinforcing spring; and Fig. 10 is a view in detail 40 and in end elevation of a part of a spring construction showing a modification of the auxiliary arch spring.

Referring to the drawings, a base frame 1 of any suitable type affords support for upright coiled body springs 2, the latter being secured in position by any suitable fastening means. A series of U-shaped braces 3 connect the corresponding intermediate coils of 45 the body springs against lateral deflection.

and transfer in a measure vertical stress 55 from one spring to another. The U-strips are readily secured as desired by clenching down their flanges 3 over the inserted spring turns but these may be replaced by other forms of braces that are suitably 60 clipped or otherwise connected to the coils. As another detail of good mechanical construction the braces which connect the intermediate springs are not only in short lengths and disposed in pairs but are ar- 65 ranged on opposite sides of the springs in alternation so that there is less tendency of the springs to cant or tilt when under load. At the ends of the structure the body springs are preferably connected by a pair 70 of braces 4 that run for the entire width of the structure. These may be U-shaped and clenched upon the coils as are the others or, like the others, may be formed of any suitable rods or strips. Similarly the 75 marginal strips 5 along the front and back of the springs are continuous throughout the length of the structure and may be single as indicated or disposed in pairs as are the end strips 4 to meet various require- 80 ments of service. Where the structure is of considerable width, as for use on a coach seat, it is preferable to reinforce the center body springs with a pair of braces 6 that are clamped on the intermediate turns of 85 the springs or suitably clipped thereto according to the nature of the brace.

Auxiliary springs 7 extend across the structure, the end turns of the springs being suitably connected to the braces which 90 connects the intermediate coils. In the preferred form the auxiliaries are in the form of arches that may have considerable camber as indicated in Fig. 2 or may be substantially straight as indicated in Fig. 10, 95 with spring coils 8 near each end, the portion 9 of the auxiliary beyond the coil being bent to overlie the inner brace 4 while its extremity is clamped in or clipped to the outer brace 4. The inner brace 4 lies be- 100 tween the coil 8 and the arm 9 in the angle formed by an abrupt bend of the latter and this serves to anchor the arch firmly against upward displacement. The arch preferably overlies the intermediate braces 3 at least 105 for a portion of its length. Where the seat is formed of two sections as indicated in Fig. 1 or more properly speaking with the

intermediate pairs of braces 6, the auxiliaries 7 engage the braces 6 alternately from opposite sides whereby the load is effectively prevented from imposing any side strain upon the body springs from the auxiliaries. If desired, other cross auxiliaries 10, as indicated in Fig. 1, may be used and these may be either arched or straight.

A hair roll 11 consisting of an outer casing 12 stuffed with suitable material extends around the margin of the seat, resting upon sets of light resilient rim wires 12^a. The latter are held in spaced relation on the tops of the body springs as for example, 15 by tongues or lips 13 struck up from flat metal strips 14 that span the top coils. The casing 12 is anchored to the rim wires and the outer marginal member 15 of the main structure by any suitable clip or stay. Such 20 fastening means may be in the form of figure 8 clips 16 that are hooked over welt cords or wire 17 sewed into the margins of the casing cover 12. Or the fastening means may consist of double ended clips whose 25 body portions 18 are thrust through the roll and whose downturned arms 19 are hooked around the outer main member 15 and inner rim wire 12 as indicated in Fig. 5. Another form of fastening consists of a welt wire 20 sewed into the depending margins of the casing 12 with depending off-sets 21 at intervals that may be bent around the main and auxiliary rim wires. If greater strength and durability is required an outer covering 30 35 22 may overlie the casing of the roll and be provided with a welted or wired edge 23 that is secured by suitable clips to the supporting rim wires.

In the use of the structure as shown any 40 load that is imposed thereon is carried at the edges of the structure by the hair roll and is supported in such manner that the upholstery is not permanently deformed even under long use. As the upper portions 45 of the inner body springs are free to be depressed independently, a soft cushioning effect is produced. Under severe shock the load is resisted in part by the auxiliary springs which transmit it throughout the 50 structure so that the load as the springs approach full compression is practically carried by every spring. Thus any severe local shock is transmitted to the entire structure and the load is prevented from compressing 55 the springs fully against the base.

The body springs as shown herein, are of the upright hour-glass type but they may be of any preferred form and may be built up of two or more springs of different 60 gages in superposed relation, such arrangement being common in seats of standard construction that do not employ the auxiliaries.

Obviously, changes in the details of construction may be made without departing

from the spirit of my invention and I do not care to limit myself to any particular form or arrangement of parts.

What I claim is:—

1. An upholstery spring structure comprising upright body springs secured in fixed relation, auxiliary rim wires supported by the outer body springs, upholstery resting upon and supported solely by the auxiliary rim wires, and auxiliary spring members supported on the lower portions of the body springs and adapted to coöperate with the body springs when the latter are partially depressed. 70

2. An upholstery spring structure comprising upright body springs secured in fixed relation, auxiliary rim wires supported by the outer body springs, upholstery resting upon and supported solely by the auxiliary rim wires, and braces connecting intermediate coils of the body springs and transmitting the load imposed by the auxiliary rim wires throughout the body springs. 80

3. A spring structure comprising a base, upright body springs secured thereon, auxiliary rim wires supported on the outer body springs, an upholstery roll supported on and secured to the auxiliary rim wires, the roll and auxiliary rim wires transmitting local pressure along the entire margin of the structure and auxiliary spring members spanning portions of the structure and supported near their ends by the lower portions of the body springs. 90

4. A spring structure comprising a base, upright body springs secured thereon, spring rim wires resting on the outer turns of the marginal body springs, upholstery rolls secured to and supported by the auxiliary rim 105 wires whereby local load along the margin is transmitted throughout the length of the structure to the body springs, braces connecting the intermediate coils of the body springs and arch auxiliary springs spanning 110 the intervals between certain of the body springs to the intermediate coils of which the end portions of the auxiliaries are secured.

5. A spring structure comprising a base, 115 upright body springs secured thereon, braces connecting intermediate coils of the body springs for transmitting pressure from one to the other, auxiliary springs spanning the intervals between certain of the body 120 springs supported by the lower turns of the body springs, the braces coöperating to distribute load imposed by the auxiliary springs upon the body springs throughout the lower turns of the latter, upholstery rolls along the margins of the structure on the body springs, and auxiliary rim wires supporting the rolls and transmitting any load imposed thereon throughout the series 125 of contiguous body and auxiliary springs. 130

6. A spring structure comprising a base, body springs supported thereon, auxiliary springs supported near the ends by lower turns of the body springs, braces connecting the intermediate turns of the body springs and transmitting load imposed by the auxiliary springs throughout the lower turns of the body springs, auxiliary rim wires on certain of the body springs for transmitting load throughout the upper turns of the contiguous body springs and upholstery rolls secured on and supported by the auxiliary rim wires. 40
7. In a spring structure, means for transmitting load through the upper turns of certain of the body springs comprising auxiliary rim wire members lying on the upper turns of certain of the body springs, an upholstery roll with casing of flexible fabric resting on the auxiliary rim wire members, and means connecting the flexible casing to the outer rim wire members. 45
8. In a spring structure, means for transmitting load through the upper turns of certain of the body springs comprising auxiliary rim wire members lying on the upper turns of certain of the body springs, an upholstery roll with casing of flexible fabric resting on the auxiliary rim wire members, reinforcing marginal members secured in the flexible casing, and means for securing said members to adjacent rim wire members. 50
9. In a spring structure having upright body springs, means for transmitting load to the marginal body springs comprising spacing members spanning the upper turns of the marginal turns, spring rim wire members secured in parallel relation on the spacing members, an upholstery roll with flexible casing supported on the auxiliary rim wire members, reinforcing holding members secured in the casing along the sides of the roll and members depending from the reinforcing members and engaging the adjacent rim wire members. 55
10. A spring structure comprising a base, upright body springs mounted thereon, horizontally disposed brace members connecting opposite sides of the intermediate turns of certain of the body springs, horizontally disposed brace members connecting intermediate turns of the other body springs in substantially the plane of the braces disposed in pairs, auxiliary arch springs secured near their extremities to the lower turns of certain of the body springs and supported thereon by the pairs of braces, the auxiliary springs when under load cooperating with all the braces to transmit pressure to the lower turns of all of the body springs, auxiliary rim wire members secured in spaced relation on the upper turns of the marginal body springs, and an upholstery roll resting on the rim wire members to which it is secured. 60
